No. 786,410.

PATENTED APR. 4, 1905.

H. H. CUMMINGS.

THREAD CONTROLLING MECHANISM FOR SEWING MACHINES.

APPLICATION FILED SEPT. 21, 1903.

UNITED STATES PATENT OFFICE.

HENRY H. CUMMINGS, OF MALDEN, MASSACHUSETTS, ASSIGNOR, BY MESNE ASSIGNMENTS, TO UNION LOCK STITCH COMPANY, OF BOSTON, MASSACHUSETTS, A CORPORATION OF MAINE.

THREAD-CONTROLLING MECHANISM FOR SEWING-MACHINES.

SPECIFICATION forming part of Letters Patent No. 786,410, dated April 4, 1905.

Application filed September 21, 1903. Serial No. 173,969.

To all whom it may concern:

Be it known that I, HENRY H. CUMMINGS, a citizen of the United States, residing at Malden, in the county of Middlesex, State of Massachusetts, have invented a certain new and useful Improvement in Thread-Controlling Mechanism for Sewing-Machines, of which the following is a specification, reference being had therein to the accompanying drawings.

10 My invention has relation in general to sewing-machines of the class employing in combination a hooked needle, a looper to place the thread within the open eye of the said needle, and a so-called "thread-finger" to engage the thread between the last stitch in the work and the looper and pull out the thread into a bight or loop before the thread is placed within the eye of the needle by the looper preliminary to the movement of the needle in the formation 15 of the next stitch.

More particularly, the invention relates to the means by which the looper and thread-finger are actuated.

The general aims of the invention are to 25 reduce the number of the working parts which are employed at the outer end of the overhanging arm or gooseneck of a sewing-machine, to simplify the construction and reduce the cost thereof, and to avoid crowding.

30 The invention consists in an improved construction and combination of parts for actuating the looper and thread-finger, which I have illustrated in the accompanying drawings, in which—

35 Figure 1 shows in end elevation portion of a sewing-machine having the invention applied thereto. Fig. 2 is a view of the same, mainly in section, in a vertical plane parallel with the axis of the actuating-shaft.

40 To assist in the presentation of the invention, I have shown in the drawings certain of the parts which in a sewing-machine are adjacent the devices in which the invention resides, and I shall refer briefly thereto in the 45 course of the description; but it is to be understood that the said parts form no portion of the invention and are presented merely for convenience and that the invention is not re-

stricted to employment in the precise connection which is illustrated.

Having reference to the drawings, at 1 is shown portion of the overhanging arm or gooseneck of a sewing-machine, a portion of the rotating shaft which extends within the said arm or gooseneck being represented at 50 2 and a bearing for the said shaft being shown at 3. At 4 is shown the laterally-movable head, which is located at the outer end of the said arm or gooseneck and to which are applied the awl-bar 5, carrying the awl 6, and 55 the presser-bar 7, carrying the presser-foot 8. The awl-bar and presser-bar are mounted, as shown, within guideways with which the said head is formed, with capacity to move vertically therein substantially as usual. The 60 actuating connections for the awl-bar are shown, they comprising the disk 9, which is mounted upon the outer end of the rotating shaft 2, the crank-pin 10, that is carried by the said disk, and the link 11, connecting the 65 said crank-pin with the awl-bar. A hooked needle is shown at 12. The work-support is indicated at 13. In the present instance the needle 12 is arranged to work upward from below through the material which is to be 70 stitched, the awl-bar and awl being arranged at the upper side of the said material.

At 14 14 are thread-guiding sheaves or rolls past which the thread which is fed to the needle is led on its way from the source of supply to the latter. The said sheaves or rolls are mounted on a small bracket 141, which is connected to the head 4.

15 is a sheave or roll which is adapted to engage with the thread intermediate the rolls 85 14 14. The sheave or roll 15 is mounted upon the lower end of the take-up arm or lever 151, the latter being attached to a rock-shaft 152, which is journaled in a bearing 1521, with which the outer end of the arm or gooseneck 90 is provided, the said rock-shaft 152 having in connection therewith a second arm 153, which latter is joined, by means of a link 154, to an operating arm or lever 155, the latter being pivoted at 156 within the arm or gooseneck 95 1 and provided with a roll 157, Fig. 2, which

works in a cam-groove that is formed in one side of the disk 7. By means of the cam-groove and operating connections the take-up arm and its sheave or roll are actuated with 5 the required timing.

The foregoing devices form no part of the present invention and may be varied or replaced as found desirable in practice.

The looper is shown at 16 and the thread-finger at 17. I will now describe the improved combination and arrangement of parts by means of which the looper and thread-finger are actuated. The looper 16 is carried by one arm of a lever 161, which latter is 10 mounted upon a pivotal stud 162 with capacity to swing, so as to carry the delivery end of the looper transversely with relation to the needle 12. The said pivotal stud 162 projects horizontally from the collar 163, which is 15 sleeved upon the projecting end of a short rock-shaft 172, the latter being fitted to a bearing at 173, which is provided therefor in the arm or gooseneck 1. The collar 163, with its stud 162, turns around the said rock-shaft in 20 order to permit the movement of lever 161, which carries the delivery end of the looper back and forth in the direction of the line of feed. The lever 161 is actuated by means of a cam portion with which the disk 9 is 25 provided. Thus upon the upper arm of the said lever is mounted a roll 164, working in a cam-groove 165, which is formed in the periphery of the disk 9. The cam-groove 165 is varied in its direction both radially with relation to 30 the axis of the shaft 2 and transversely or parallel with the said axis in order to occasion the compound movement of the lever 161 and looper 16, by which the delivery end of the looper is caused to travel in the required path 35 relative to the hooked end of the needle. In order to compensate for such wear as may occur, the sides of the groove 165 are made inclined toward each other, as shown, so that the groove is essentially V-shaped, and the roll 166 is correspondingly tapered toward its 40 periphery to fit the groove. In practice the roll is held pressed into the groove through the aid of a spring acting in connection with lever 161 in opposition to the outward radial 45 throw of the cam-groove. This spring has been omitted from the drawings in order to render the latter simpler and clearer. The thread-finger 17 is carried by the lower end 50 of an arm 171, the said arm being fast upon the rock-shaft 172, which is journaled, as aforesaid, in the bearing that is provided at 173 within the arm or gooseneck 1. The rock-shaft 172 is provided with an arm 174, the said arm carrying a roll at 175, engaging with 55 the periphery of a cam 176, which is fast upon the shaft 2. In practice a spring is employed in connection with the arm 174 to aid in holding the roll 175 in contact with the cam 176; but the said spring has been omitted from the 60 drawings in order to simplify the latter. 65

The rock-shaft 172, as will be seen, in addition to supporting and operating the thread-finger 17 serves to support the swinging mount or carrier 163 162 for the lever 161 of the looper, thereby dispensing with a separate 70 support for said mount or carrier. This, as will be perceived from inspection of the drawings, is an important matter, owing to the crowded condition of the parts within the outer end of the arm or gooseneck and to the 75 compact relations in which such parts are required to be assembled.

The described devices for actuating the looper and thread-finger are simple and comprise but a small number of working parts 80 reliable in their action, not liable to get out of order, and easy to adjust and repair.

I have shown in the drawings a yielding construction of thread-finger by which the thread-finger is permitted to yield, so as to 85 compensate for any lack of correspondence in the relative timing between the same and the other parts which are concerned in the process of making stitches in the machine to which the invention is applied, thereby in case, for 90 instance, in a machine in which lock-stitches are produced through the employment of a shuttle the shuttle should take up the loop of needle-thread in expanding the same as it passes therethrough faster than the thread is 95 given up or surrendered by the return movement of the thread-finger after the latter has extended the bight or loop of said thread, the thread-finger is enabled to yield, so as to relieve the strain, and thus obviate injury to the 100 thread. In the drawings the thread-finger 17 is shown provided with a pivot or journal 18, which is fitted to a bearing at 181, with which the arm 171 is provided, and in connection with the thread-finger a spring, as 182, is provided, the said spring in the present instance 105 having one end thereof passed through a diametrical hole in the pivot or journal 18 and the other end thereof engaged with the arm 171. When the strain becomes sufficiently 110 great, the spring 182 will give or yield, so as to permit the thread-finger to turn upon its pivot or journal.

I claim as my invention—

1. In a sewing-machine, in combination, a 115 hooked needle, a thread-finger, a rock-shaft with which the said thread-finger is connected, means to actuate the said rock-shaft and thread-finger, a looper, a support for said looper which is swiveled on said rock-shaft to turn around the same and on which support the looper is 120 pivoted to swing transversely, and means engaging with said looper to cause it to describe the required path relative to the hooked needle.

2. In a sewing-machine, in combination, a 125 hooked needle, a thread-finger, a rock-shaft with which the said thread-finger is connected, means to actuate the said rock-shaft and thread-finger, a looper, a support for said looper which is swiveled on said rock-shaft to turn around 130

the same and on which support the looper is pivoted to move transversely, and a cam engaging with said looper and acting to impart thereto movement of which the components 5 are in directions at right angles to each other.

3. In a sewing-machine, in combination, the thread-finger, a rock-shaft with which the said thread-finger is connected, and means for operating the said rock-shaft to move the thread-finger, of the looper, the lever by which the same is carried provided with a V-shaped roll or stud, a rotating cam having a V-shaped groove with lateral and radial throws to pro-

duce the required movements of the looper, and a pivotal stud for the said lever on which 15 the latter is mounted to swing transversely, the said stud being sleeved to swing in a vertical plane upon the rock-shaft of the thread-finger.

In testimony whereof I affix my signature in 20 presence of two witnesses.

HENRY H. CUMMINGS.
